SPRING MATTRESS CONSTRUCTION

Eugene Joseph Hood, Carthage, Mo., assignor to
 Frank B. Williams and Harold E. Williams, both
 of Carthage, Mo.

Application March 24, 1948, Serial No. 16,759

5 Claims. (Cl. 5—351)

1

This invention relates to new and useful improvements in a spring mattress structure, and has particular reference to a spring mattress structure providing a support for padding or upholstery to be carried by said mattress, whereby said padding or upholstery is prevented from working into the spaces within and between the component springs.

The principal object of the present invention is the provision, in a spring mattress having a plurality of helical springs arranged in rows with the adjacent portions of their top and bottom end coils joined by a plurality of helical binder coils extending in substantially parallel relation across the surface of said mattress, of a padding support comprising a plurality of parallel support wires extending transversely to said binder coils, said supporting wires being positioned entirely on one side of the wires forming said binder coils and between adjacent loops of said coils, and a retaining wire positioned axially in each of said binder coils, whereby said supporting wires are retained between the loops of the binder coils.

Other objects are simplicity and economy of construction, ease of assembly, and adaptability of the padding support to be applied to previously fabricated spring mattresses.

With these objects in view, as well as other objects which will appear in the course of the specification, reference will be had to the drawing, wherein—

Fig. 1 is a plan view of a spring mattress structure embodying the present invention.

Fig. 2 is a sectional view taken on line II—II of Fig. 1.

Fig. 3 is an enlarged fragmentary section taken on line III—III of Fig. 1.

Like reference numerals apply to similar parts throughout the several views, and the numeral 2 applies to each of a plurality of helical springs, said springs being axially parallel and arranged in a plurality of parallel rows as shown in Fig. 1 to form a mattress. Any number of springs may, of course, be used, depending on the size of the mattress or cushion to be built. The top loops 4 and the bottom loops 6 of said springs each lie substantially in a horizontal plane. The top and bottom marginal edges of the mattress thus formed are bound by helical binder coils of relatively small diameter, coils 8 being coiled about the outer portions of the top and bottom end loops of springs 2 at each end of the spring rows, and coils 10 being coiled about the outer portions of the top and bottom end loops of

springs 2 in each of the outer spring rows. These end loops of adjacent springs 2 in each row overlap slightly, and are joined by binder coils 12, which are coiled about said overlapping portions of the spring loops. Coils 12 are parallel to coils 8, and extend substantially across the mattress between corresponding springs of each row. Each of coils 8, 10 and 12 is securely anchored in place by having its end portion wrapped tightly about an adjacent loop of one of the springs 2.

The joining of helical springs by helical binding coils as described is not new, and is claimed only in combination with the hereinafter described padding support. Said padding support comprises a plurality of supporting wires 14 extending in parallel, spaced apart relation across the top of the mattress. Said wires are parallel to binder coils 10 and transverse to coils 12, and are secured in place by twisting the end portions of each wire around a convenient loop of the adjacent coil 8, as at 16. Each of supporting wires 14 passes beneath the wires from which coils 12 are formed, but is positioned between adjacent pairs of loops of each of said coils, as best shown in Fig. 3.

Thus, each wire 14 is substantially secured against lateral movement at each point it intersects a coil 12, except that were wires 14 not further supported they could be pushed downwardly from coils 12 and become displaced. This is overcome by inserting a retaining wire 18 axially through each of coils 12, said wire passing beneath each of wires 14. The ends of wires 18 are twisted around the end loops of coils 12 as at 20. Each of wires 14 is thus supported firmly at each of coils 12, since it passes through a substantially closed loop formed by said coil and its associated retaining wire 18.

It is apparent that a simple, efficient padding support has been produced which may be attached easily to any spring mattress structure such as is used in bed mattresses, furniture cushions, automobile upholstery, and the like, and while it is inseparable from and forms a structural part of the mattress, it may be attached to a mattress previously fabricated. The spacing of support wires 14 may be regulated to provide adequate support for padding or upholstery, and said wires also provide convenient means for attaching said upholstery. Wires 14 and 18, since they extend across the mattress at right angles, and since they are anchored at each end, also serve to reinforce the mattress structurally against horizontal distortion.

It is apparent that many minor changes of design and construction could be made without departing from the spirit of the invention, and it is therefore desired to be limited only by the scope of the appended claims.

What I claim is:

1. In a spring mattress of the character described having a plurality of helical springs bound together by marginal binding members and a plurality of substantially parallel intermediate binding members extending between and joining adjacent rows of springs, a padding support comprising a plurality of parallel elongated support members extending across said mattress transversely to said intermediate binding members, and members extending across said mattress transversely to said support members and operable in conjunction with said intermediate binding members to retain each of said support members against any material lateral movement at its point of intersection with each of said intermediate binding members.

2. The combination, with a spring mattress structure comprising a plurality of helical springs arranged in parallel rows, helical binder coils which coil about the outer portions of the top and bottom loops of the marginal spring, and intermediate helical binder coils extending in parallel relation between adjacent rows of springs and coiled about the adjacent portions of the top and bottom loops of the springs in said adjacent rows, of a padding support comprising a plurality of substantially parallel support wires extending across the top of said mattress transversely to said intermediate binder coils, each of said support wires being disposed on the same side of all of said intermediate binder coils and passing between adjacent loops of each binder coil, and a retaining wire positioned axially in each of said intermediate binder coils, whereby said support wires are retained between the loops of said coils.

3. The combination, with a spring mattress structure comprising a plurality of helical springs arranged in parallel rows, helical binder coils which coil about the outer portions of the top and bottom loops of the marginal spring, and intermediate helical binder coils extending in parallel relation between adjacent rows of springs and coiled about the adjacent portions of the top and bottom loops of the springs in said adjacent rows, of a padding support comprising a plurality of substantially parallel support wires extending across the top of said mattress transversely to said intermediate binder coils and secured at their ends to said marginal binder coils, each of said support wires passing beneath the wires forming said intermediate binder coils but positioned between adjacent loops of said coils, and a retaining wire positioned axially in each of said intermediate binder coils and secured at its ends to the end loops of said coils, said re-

taining wire passing beneath each of said support wires, thereby retaining said support wires between the loops of said binder coils.

5. A spring mattress structure comprising a plurality of axially parallel helical springs arranged in parallel rows, binding means extending around the upper and lower marginal edges of the mattress thus formed and connecting said springs, intermediate binding members at the top 10 and bottom of said mattress extending transversely to said spring rows and connecting the corresponding adjacent springs of each of said rows, elongated supporting members extending in parallel relation across the upper surface of 15 said mattress transversely to said intermediate binding members, means for securing said supporting members against longitudinal movement, and elongated retaining members extending across the mattress transversely to said supporting members, each of said retaining members operating in conjunction with one of said intermediate binding members to secure each of said supporting members against material lateral movement at its point of intersection with said binding member.

20 25 30 35 40 45 50 55 60

5. A spring mattress structure comprising a plurality of vertically parallel helical springs arranged in parallel horizontal rows to form a mattress, helical binder coils extending along the upper and lower marginal edges of said mattress and coiled about the outer portions of the top and bottom end loops of said springs, intermediate binder coils extending across the upper and lower surfaces of said mattress transversely to said spring rows and each coiled around the adjacent portions of the top and bottom end loops of corresponding adjacent springs in each of said rows, parallel supporting wires extending across the top of said mattress transversely to said intermediate coils, each of said supporting wires being disposed beneath the wires forming said intermediate binder coils but passing between adjacent loops of each of said coils, means securing said supporting wires against longitudinal movement, a retaining wire positioned longitudinally within each of said intermediate binder coils and passing beneath the supporting wires intersecting said coil, and means securing said retaining wires against longitudinal movement.

EUGENE JOSEPH HOOD.
